UNITED STATES PATENT OFFICE

FRANK S. TRUMBULL, OF PROVIDENCE, RHODE ISLAND

DESIGN FOR A SHERBET GLASS OR SIMILAR ARTICLE

Application filed February 25, 1930. Serial No. 34,646. Term of patent 3½ years.

To all whom it may concern:

Be it known that I, FRANK S. TRUMBULL, a citizen of the United States, residing at Providence, in the county of Providence and State of Rhode Island, have invented a new, original, and ornamental Design for a Sherbet Glass or Similar Article, of which the following is a specification, reference being had to the accompanying drawings, forming a part thereof, in which—

Figure 1 is a front elevation of a sherbet glass or similar article showing my new design,

Figures 2 and 3, sections of the same taken on lines 2—2 and 3—3 respectively, and viewed in the directions of the respective arrows, and

Figure 4, a bottom plan view of the same. The base is of an opaque material, which contrasts in material and color with the bowl, which is transparent.

I claim:

The ornamental design for a sherbet glass or similar article, as shown and described.

FRANK S. TRUMBULL.
